UNITED STATES PATENT OFFICE

CLARENCE B. LENNEY AND GEORGE P. LENNEY, OF WARREN, OHIO, ASSIGNEES TO THE YOUNGSTOWN PRESSED STEEL COMPANY, OF WARREN, OHIO

IRONING TABLE

Application filed December 17, 1926. Serial No. 155,498.

This invention relates to a metallic collapsible fireproof ironing table and it consists in the novel features hereinafter described and claimed.

5 An object of the invention is to provide a practically and absolutely fireproof press stand the parts of which are non-inflammable with the exception of a muslin cover which is used in conjunction with the structure.

10 A further object of the invention is to provide a structure of the character stated which is devoid of the usual objectionable features found in the conventional ironing board as for instance warping, danger of fire, clumsy assemblage and awkward to adjust.

In the accompanying drawings:

Figure 1 is a side elevational view of the metallic collapsible fireproof ironing table 20 showing the parts thereof extended.

Figure 2 is an elevational view thereof showing the parts folded.

Figure 3 is an enlarged transverse sectional view of the table cut on the line 3—3 of 25 Figure 2.

Figure 4 is an under plan view of the ironing board of the table device.

Figure 5 is an enlarged fragmentary transverse sectional view of the table cut on the 30 line 5—5 of Figure 1.

Figure 6 is an enlarged detailed side elevational view of intermediate portions of the table, and

Fig. 7 is a view in detail of the pivot for 35 the clamping member.

The collapsible fireproof ironing table comprises a cabinet member 1 preferably of sheet metal and the body portion of which is surrounded by an outstanding flange 2. The 40 side portions of the flange 2 are provided at points between their ends with indentations 3 which are adapted to receive latch bolts (hereinafter described) when the parts of the device are folded or collapsed. A casing

45 member 4 is hingedly connected as at 5 with the lower end of the cabinet member 1 and the casing member 4 is provided along its edges with an upstanding flange 6. The side portions of the flange 6 are provided with recesses 7 which are located in the vicinity of

the hinge 5 and which are adapted to receive portions of the ironing board or panel cover when the same is applied and as hereinafter described. The flange 6 of the casing member 4 is adapted to fit snugly within the flange 55 2 of the cabinet member 1 when the structure is closed and as best indicated in Figure 3 of the drawings. The side flanges 6 of the casing member 4 are provided with latch bolts 8 hereinbefore described which are adapted to engage in the depression 3 of the flange 2 of the cabinet member 1 when the structure is closed, thus folding the parts in a folded or collapsed position. The cabinet member 1 60 may be mounted upon a wall surface or any 65 other suitable support as best indicated in Figure 1 of the drawings.

The casing member 4 is preferably made of sheet metal.

Hinges 9 are attached to the outer surface 70 of the casing member 4 and a leg frame 10 is pivotally connected with the hinges 9. The leg frame 10 is rectangular in form and its ends are connected with the hinges 9 and the side portions and intermediate portions of the 75 leg frame 10 are provided with an outstanding flange 11. The intermediate portion of said flange is provided with an outstanding lip or impression 12 which may serve as means for permitting the tips of the fingers to be inserted between the intermediate portion of the leg frame and the casing member 4 for lowering or extending the parts of the device.

The flange 11 of the leg frame 10 is adapted to fit snugly against the exterior surface of the flange 6 of the casing member 4. Stop members 13 are fixed to the end portion of the leg frame 10 and are adapted to engage the exterior surface of the casing member 4 when the parts are in the extended position as shown in Figure 1 and hold the leg frame 10 at a right angle to the casing member 4. The intermediate portion of the leg frame 10 rests upon the upper surface of the floor and thus the parts are securely held or supported in extended position.

An ironing panel member 14 is provided around its edge with an outstanding flange 15 which is adapted to enter within the inner surfaces of the flanges 6 of the casing mem- 100

ber 4. Straps 16 of metal are fixed to the intermediate portions of the ironing panel 14 and have outstanding intermediate portions in which bolts 17 are screw theaded. The 5 bolts 17 also pass through the casing member 4 and are provided at their outer ends with enlarged circular head 18 having knurled edges and which serve as means for holding the ironing board member 14 in a 10 fixed position with relation to the casing member 4 and also cause the casing to hold the bar 21 between the flanges 20. The ironing board member 14 is also made of sheet metal. Certain leaves of the hinges 9 are 15 secured to the under side of the casing member 4 preferably by welding. A covering sheet 19 preferably of muslin extends over the ironing board member 14 and its edge portions overlap each other and are secured at 20 the under side of the ironing board member as will be hereinafter described.

Spaced flange members 20 are secured to the under side of the ironing board member 14 and are disposed longitudinally thereof and substantially along the median longitudinal dimensions thereof. A clamping rod or bar 21 is pivoted as at 22 between the flanges 20 and is provided at its free end with a cross head 23 which may be used as a handle grip for grasping the free end of the clamping bar to swing the same with relation to the flanges. The body portion of the bar normally lies between the flanges 20 and when the cover 19 is spread over the ironing board member and its edge portion overlaps as best shown in Figure 3, the clamping bar 21 is swung between the flanges 20 whereby the overlapping portions of the cover are carried between the flanges and the said cover 19 is stretched over the ironing board 14. When the clamping bar 21 is inserted between the flanges 20 the handle portion 23 thereof will lie against the lower edges of the flanges 20 and is disposed transversely thereof. The recesses 7 which are provided at inner ends of the side portions of the flange 6 of the casing member 4 may be used as clearance spaces through which the fingers, or an instrument may be inserted for the purpose of lifting the ironing board member 14 above the casing member 4 when it is desired to remove said ironing board member from the said casing member.

As hereinbefore stated the cover 19 is fabric material, preferably muslin, and may be easily and quickly removed from the ironing board member for washing or replacement. When the casing member is closed with relation to the cabinet member the ironing board member and the cover is completely enclosed between the casing and the cabinet and consequently these parts are not exposed to the accumulation of dusts and dirt and when the ironing board member and the casing are swung to an open position the

device is ready to be used for ironing or pressing purposes.

Inasmuch as the complete structure, with the exception of the cover, is composed of metal the device does not present a fire hazard and the parts will not warp or shrink and the structure may be built in the walls of a room or may be applied to walls as desired or required. 70

From the foregoing description of the construction of our improved device, it will be seen that we have provided a simple, inexpensive and efficient means for carrying out the objects of the invention. 75

Fig. 7 shows the pivot for the clamping bar 21, said pivot including a cross pivot pin 22 mounted in the flanges 20. 80

While we have particularly described the elements best adapted to perform the functions set forth, it is obvious that various changes in form, proportion and in the minor details of construction may be resorted to without departing from the spirit or sacrificing any of the principles of the invention. 85

Having described the invention what we claim is:

1. An ironing table comprising a casing, means for supporting the casing, an ironing board supported upon the casing, spaced flanges carried at the under side of the board, a clamping bar pivoted for swinging movement between the flanges, a cover extending around the ironing board and having overlapping portions adapted to be clamped by the bar between the flanges and means for securing the casing to the board. 95 100

2. In combination with an ironing board, means for holding a cover thereon, said means including spaced longitudinally extending flanges carried on the underside of the board, a clamping bar pivoted for swinging movement and adapted to be pressed between said flanges into locking position, and means for retaining said locking bar in clamping position. 105

In testimony whereof we affix our signatures.

CLARENCE B. LENNEY.
GEORGE P. LENNEY.
